US0D1099513S

(12) United States Design Patent (10) Patent No.: US D1,099,513 S
 Tseng (45) Date of Patent:  Oct. 28, 2025

(54) PILL CONTAINER

- (71) Applicant: E-LINK PLASTIC & METAL INDUSTRIAL CO., LTD., New Taipei (TW)
- (72) Inventor: I-Ting Tseng, New Taipei (TW)
- (73) Assignee: E-LINK PLASTIC & METAL INDUSTRIAL CO., LTD., New Taipei (TW)

() Term: 15 Years(21) Appl. No.: 29/940,164(22) Filed: Apr. 30, 2024

(51) LOC (15) Cl. 03-01
 (52) U.S. Cl. USPC D3/203.2

(58) Field of Classification Search

(57) CLAIM

The ornamental design for a pill container as shown.

DESCRIPTION

FIG. 1 is a perspective view of a pill container showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.
